UNITED STATES PATENT OFFICE.

EDGAR E. GREVE, OF BELLEVUE, PENNSYLVANIA, ASSIGNOR TO OIL WELL SUPPLY COMPANY, OF PITTSBURGH, PENNSYLVANIA, A CORPORATION OF PENNSYLVANIA.

PITMAN CONNECTION FOR OIL-WELL APPARATUS.

1,420,033.

Specification of Letters Patent. Patented June 20, 1922.

Application filed October 18, 1918. Serial No. 258,725.

To all whom it may concern:

Be it known that I, EDGAR E. GREVE, a citizen of the United States, residing at Bellevue, in the county of Allegheny and 5 State of Pennsylvania, have invented certain new and useful Improvements in Pitman Connections for Oil-Well Apparatus, of which the following is a specification.

The prime object of my invention is to 10 provide a new and improved wrist-pin structure particularly designed for use in connection with oil well apparatus, the present invention especially relating to that class of apparatus patented to me January 18, 1916, 15 No. 1,169,076.

In the patent above mentioned and in the present invention, I have provided, in combination with a pitman for oil well apparatus, a simple and efficient wrist-pin structure designed for connecting the pitman to its crank.

A further object of the present invention, in addition to providing a simple and efficient connection between the pitman and its 25 crank, is to provide a construction that may be readily utilized in the operation of spudding without the necessity of employing a spud pulley or wheel and other elements heretofore necessarily employed while spudding.

Other objects of the present invention are, to provide simple means for lubricating the working parts without removing the pitman from the wrist-pin structure and means for 35 taking up wear.

In the accompanying drawings which illustrate applications of my invention,

Fig. 1 is a part sectional and a part elevational view showing the lower portion of 40 the pitman and the wrist-pin structure, the section being taken on line 1—1 of Fig. 2;

Fig. 2, a part plan and a part sectional view, the section being taken on line 2—2 of Fig. 1; and

Fig. 3, an elevational view of a portion 45 of an oil well apparatus showing my invention in connection therewith.

Referring to the drawings, 1 designates a walking beam of a portion of an oil well 50 rigging, and 2 a pitman secured to the end of the beam by means of a stirrup 3.

4 designates a crank which is attached to the shaft of a band wheel 5, the crank being of the usual type and having a plurality of 55 openings to receive the wrist-pin. 6 design-

nates a spud rope having one end secured to the wrist-pin structure and the other end loosely connected with a cable 7. The cable 7 is connected with a drum 8 mounted on the shaft of bull wheel 9.

As illustrated and as preferred, the pitman 2 is preferably made of metal and is provided at its lower end with a casing or block 10 having a frusto-conical shaped opening 11 adapted to receive the wrist-pin 60 structure. Carried by the casing is a pair of spring controlled catch devices 12 each having an inwardly projected engaging member 13, the latter being adapted to engage the peripheral surface of the wrist-pin 70 structure.

The wrist-pin structure comprises a wrist-pin proper 14 having a threaded end 15, a collar 16, an end flange 17, a centrally disposed opening 18, the walls of which are 75 threaded, and a small duct 18^a in communication with the opening 18. The purpose of the opening 18 is to receive a quantity of grease for lubricating purposes.

19 designates an adjustable threaded plug 80 adapted to be entered in the opening 18 and engage the threaded wall thereof. Said threaded plug is accessible through an opening 20 formed in the casing 10. Mounted on the wrist-pin 14 and disposed between 85 the collar 16 and the flange 17 is a flange bearing element 21 having its flange portion 22 formed with apertures 23. The bearing element 21 is made in two segments in order that it may be assembled about the flanged 90 wrist-pin. 24 designates an outer member of the wrist-pin structure adapted to encircle the inner member 21 and be secured thereto by means of bolts 25 passed through said outer member and through the flanged portion 22 of member 21.

Member 24 has a peripheral frusto-conical configuration, the same being complementary with the opening 11 of the pitman casing 10. 26 designates a groove located 100 in the member 24, said groove being adapted to receive the engaging members 13 of the catch device, whereby the wrist-pin structure is securely locked within the casing 10.

An additional function of groove 26 is to 105 receive and maintain the looped end of the spud rope 6 in the desired position during the operation of spudding.

Means for taking up wear are interposed 110 between bearing member 21 and the outer

member 24 of the wrist-pin structure and as shown, these means include a wedge 27 and a co-operating screw bolt 28. 30 designates locking means for screw bolt 28.

5 For convenience in handling the heavy pitman and its block or casing, the block is provided with a roller 29.

10 It will be seen that the construction herein described is of such a character that the pitman and its crank may be readily connected and disconnected, and after the pitman is removed from and swung to one side of the assembled wrist-pin structure, said structure may be utilized for spudding by simply placing 15 the loop of the spud rope over the wrist-pin.

20 The weight, number and cost of the elements entering into constructions of this character and the manipulations of the parts are of considerable importance, and it has been my aim to reduce the number of parts as much as possible, and at the same time provide means whereby the parts may be 25 easily and readily positioned to meet working requirements.

What I claim is:

1. The combination with a pitman and a crank, of means for detachably connecting the pitman and crank including a wrist-pin 30 structure comprising a wrist-pin proper, an inner member, an annular outer member having an outer peripheral configuration and provided with a peripheral groove, said members being concentrically disposed, and 35 means for securing the members together, said pitman having means thereon for engaging in said groove for detachably holding the pitman in connection with the crank.

2. The combination with a pitman and a 40 crank, of means for detachably connecting the pitman and crank including a wrist-pin structure comprising a wrist-pin proper, an inner bearing member mounted on the wrist-pin, an outer member having a frusto-conical 45 peripheral configuration and provided with a peripheral groove, said members being concentrically disposed, means for securing the members together, means on the pitman having a frusto-conical surface for engagement with the periphery of the outer member, and means on the pitman for engagement in the peripheral groove.

3. A wrist-pin structure including a wrist-pin proper, an inner divided bearing member, an outer member having an annular peripheral configuration and provided with a peripheral groove, said members being concentrically disposed, adjustable wedge means interposed between the members, and other 55 means for securing the members together, said groove providing means for engagement with a spudding rope or for cooperating with the pitman.

4. A wrist-pin structure including a wrist-pin proper, an inner bearing member having

an annular flange and mounted on the wrist-pin, an outer member having a frusto-conical peripheral configuration and provided with a peripheral groove, said members being concentrically disposed, wedge means interposed between the members co-axial with the wrist-pin, and locking means passed through the outer member and the flange of the inner member for securing the members together.

5. The combination with a pitman having a casing at its lower end adapted to receive a wrist-pin structure, an assembled wrist-pin structure adapted to be entered in and removed from the casing, means for detachably securing the wrist-pin to the casing and lubricating means for the wrist-pin structure and contained in the wrist-pin, said casing having an opening through which the lubricating means are accessible.

6. The combination with a pitman having a frusto-conical shaped hollow casing, a wrist-pin structure having a frusto-conical peripheral configuration and an annular groove adapted to be entered in the casing, and locking means carried by the pitman and 90 engaging the groove of the wrist-pin structure.

7. The combination with a pitman having an opening, and a crank, of means for adjustably connecting the crank and pitman comprising an assembled wrist-pin structure adapted to be bodily entered in the pitman opening, said structure including an outer member having a conical peripheral configuration substantially complementary to the pitman opening and provided with a groove, and locking means carried by the pitman and 100 engaging the groove of the wrist-pin structure.

8. The combination with a pitman having a casing at its lower end which is provided with a wrist-pin structure engaging portion, of a wrist-pin, a wrist-pin structure journaled thereon which has a grooved periphery, means on the wrist-pin for preventing the lateral movement of the wrist-pin structure, means on the wrist-pin structure adapted to slidably engage the wrist-pin structure engaging portion of said casing, and means on the casing engaging the wrist-pin structures for retaining the casing and wrist-pin structure in operative position, said means being operable to release the casing from engagement with the wrist-pin structure by moving the casing and pitman in a direction 110 co-axial with the wrist-pin.

9. The combination with a pitman having a casing at its lower end, which casing is provided with a frusto-conical shaped wrist-pin structure engaging portion therein, of a 125 wrist-pin, a wrist-pin structure journaled thereon, means for preventing lateral movement of the wrist-pin structure, a frusto-conical peripheral surface on said wrist-pin structure adapted to slidably engage the 130

frusto-conical wrist-pin engaging portion of said casing and having an annular groove therein, catch devices on the casing adapted to cooperate with the groove to prevent 5 lateral movement of the pitman in one direction, said frusto-conical portions preventing such movement in the opposite direction, said catch devices being operable to permit

the pitman to be disconnected from the wrist-pin structure. 10

In testimony whereof I affix my signature in presence of two witnesses.

EDGAR E. GREVE.
